101.

Ady Forward
Letters Patent

Am. Ady informe to in these letters Patent and making part of the same containing a description in the words of the said Ady Forward, himself of his improvement in the machine or closed vessel for manufacturing the processes of Notch and Ando and also certain machinery, apparatus and utensils, to be used in the said manufacture, and in the drawing, dying and washing of Wool, with flax, flax, flax, flax, flax, flax, flax, or otherwise, also in the dying of silk, cotton, linen and other textile or organic substances.

The principle articles, on which my claims are founded: 1° On the construction of a closed vessel (and its employment) as well as certain apparatus, methods, and processes for manufacturing the processes of Notch and of Ando. - That vessel bearing a cylindrical or any other form, placed horizontally or vertically, resting on itself or being steady and the materials being stored into it by machinery or without it.

2° On the importance of passing wool or the like, blanket &c. into an acid bath, in order of cleaning it thoroughly, and on the general advantages arising from the use of this bath, not only for washing intended to be done by the processes of now, but also for all kinds of woolen materials, whether intended to be dyed by the ordinary processes not.

3° On the means of producing a white textile substance, an uniform separation of the fiber and dead side of wool, or an evide more of quality, by means of a current of air heated and blown upon them by means of a bellaz in a particular apparatus.

4° On the means of dying the fibres of copper by passing first of the fibre, 5° on the means of bleaching black, orange and a great many other colors with or without a blue tint, by bleaching and combining the oxide of iron with almost all the coloring materials known. The blue tint when desired being given by passing acid or indigo indigo being used employed before, during or after the bleaching of the oxide of iron, by means of pure acid, or materials

100.

intended for blue to give them a peculiar shade. The bath, of oxide of iron, of fericic acid and other coloring substances, being used below or at boiling heat. 6th On the method of expressing the liquid from the cloth, &c., as they pass out of the bath, by means of screwing rollers, suspended from the cylinder.

7th On the pigment of a colored stone to expel the humidity from the cloth, &c. 8th On the adaptation of various systems, of vessels, eccentric, bushy &c. to the construction and employment of a machine for washing wool, and on the employment of certain vessels, apparatus and utensils, and their arrangement as a means of performing the general and particular processes for which they are intended, not only for washing wool, and other materials to be dyed by the process described but also every kind of material in any dye house.

9th On the principles, the character, the effects, and consequent results of the preceding article, either combined with the means, and processes of the plant granted me under the date of the fourteenth day December 1832, or not, and either used in the whole, or in part in the manufacture of the dye house.

Many of the things which are represented in the drawings, called with this specification, and detailed in the various processes, are not strictly speaking my invention, but I claim them only as respects the practical and special application to which I adapt them, in the process of washing, scouring, dyeing and manufacturing.

Process of manufacturing the frizziates.

The different vessels and apparatus described in plate 1st & 2nd being erected and placed in a place sufficiently large. Fit the cast iron cylinder M Figure 1. to a low red heat as it has been previously described in the specification of my patent of December 1832. Place the front disk I and its pin on the front part of the cylinder, and the pin a little after having introduced it into the hole of the collar of the disk and the cylinder set the plates and description of them depicted in the Patent Office.

Place the cylinder on the cylinder so that the sand pointed end

it rests about a foot on the support J. The cross bars K being placed horizontally in the axis, then fix the hinder disk N on the axis - so by means of the pin or wedge L, closed by means of the hinge D of the movable part M of the disk (8), then throw the before mentioned mixtures quickly into the cylinder.

thus done remove such part of the mixture as may remain behind the part of the disk N by means of a broom, raise the part M and place the ring O against the parts M and N, by this means the upper part M will be firmly closed. During this time lift the groove L of the door of the cylinder and the spring K of the door S, with flotting earth mixed with hair to form a little of a proper consistency at the same time the prolongation B of the agitator must be fitted into the stuffing box and later stuffed all round the agitator as far as O. On lifting the door T, on its hinge the extending piece R. will be reacted. Then introduce the square end of the part H. of the agitator into the fork Q of the hinder part. Place them so that the holes H. and S. come opposite to each other, so as to pass the pin P through them, which must be bent a little so that it may not fall out of the holes without force.

that done push the door against the extending piece R. pass a wire in the ring U. of the collar A and free them so that the parts R. and T may be closely joined by means of the bars and pieces marked B. in the form of the letter S, which pass underneath the iron collar D. guided by the staple P. The projecting part V. entering the groove L. and later the entrance to the cylinder. Then introduce the wedge L. of the stuffing box in the agitator B. pass a wire in the ring U. of its collar. Pass the bars or wedges L. against the bottom O. of the stuffing box (previously coating with lard in the manner already described) these 2 parts of the different pieces. Put the second collar E. upon the agitator B. raise the setting piece A. of the support d (9) put the two pins C. into the holes of the pins A and d. pass the key or pin C. into the space between the head of the screw E. and place the toothed wheel

✓ *6. with agitator.* The teeth of this wheel entering those of the brass wheel F. Then place the pin g into the hole made at the end of the axis of the agitator; next turn the handle I, applied upon the axis of the wheel F, and thus continually start up the small and other volatilities submitted to calcination in the closed cylinder (10). The gaseous products will be passed into the first vessel of the Meulig apparatus, by means of the tube F, and afterwards (by means of the tubes B,) into the other vessels B. Such of these gaseous substances are condensable, as the empty potassium oil and the ammoniacal gas, will be condensed. The carbonic and hydrogen gas will escape by the tube A.

When the agitator has been made to work at various or work in the cylinder, by means of the screw; a distance between two of the brasses or iron bars K, the workman who turns the handle I, must pass to the other side of the agitator; and turn the handle in the same way by which means the agitator will be worked in the same direction of the first movement, when it arrives at the same distance he must again pass to the other side, and proceed thus, during the operation of calcining, but more quickly than at the first turning, continue thus about one hour and then in much more quickly, and then he finds less resistance in the interior of the cylinder, and that the movement is more easy; (and to this great attention must be paid,) he must then turn very quick for about 10 or 12 minutes, for then the substances are in general brought near to the desired state of calcination; a few minutes before previously he must open the aperture L, and if the little smoke is apparent, then the calcination, it may be said, is completed, having arrived at its proper period.

Then immediately proceed to discharge the cylinder thus, take out the pin g of the wheel G, at the same time letting out those of the rolling pins z, the support d, and the screw (if the supports are fixed under the carriage figure 21). Then remove the carriage from underneath the extending flue of the agitator.

5

103

After the door *P.* is pushed back, unfasten the collar *A.* of the door and open it half way, take out the pan *P.* which holds the two parts of the agitator, open the door entirely and by means of a brush of iron, which must be passed into the handle *S* of the disk, draw the agitator *of the cylinder* quickly and let the calcined matter fall into the conical moulds *P.* of the carriage *figure 3 (11)*, fixed under the extension of the cylinder *to.* On withdrawing the agitator from the cylinder it must be held by the hook *B.* of the crane *figure 3.* The agitator, being withdrawn from the cylinder, the little calcined matter which remains, adhering to it, must be removed by means of a brush formed of iron wires, and with a rake remove each of the calcined matter from the cylinder as was not withdrawn by the front disk *I.* of the agitator. Take the carriage from under the extension of the cylinder, and immediately recharge the cylinder *to.* in the first instance. A mixture of the denoted materials should always be had in readiness for that purpose. The calcined matter being cooled *(12)* consigned to the moistening barrel *figure 4.* and when introduced as described in the specification of my Patent of December 1822, put it into the guard *A.* of the boiler of the steam vessel *Figure 5.*

Charge the boiler to about three feet of its height, and then admit water (or afterwards the weak solution in the reservoir) raised by the pump *Figure 6.* to a little short of one foot of the lid.

Things being thus disposed, fill the reservoir *D* to about half its height with a mixture of one part of sulphur increased to ten parts of water. Screw the bell *E.* on the axis *G.* of the agitator, until the lower part of it is about two inches from the bottom of the reservoir *D.* Then place the tube *B.* with its cork open into the first vessel of the flasks, *opposite* that is, into the first of two vessels, placed at a little distance from the boiler *figure 5.* fill the first one to about half its height, with a solution of the mixture of lime

which we will suppose to be about 15 degrees of the anerometer for salts, and in the second vessel (left entirely open) put about as much water (as in the neighbouring vessel), calculated as in vessel D. This must then be placed under the boiler and the substance kept boiling, for about one hour and a half as before prescribed, and during this time the matter in the boiler must be continually stirred by means of a handle fixed on the axis, one of the boat wheels E. after this a linen cloth must be spread over the grating A of the filter or figure 6, and be fastened to the frame I, and drawn tight against the grating I. the cork C being closed. Between the doors D & E, tightly fastened by the wedge B. the gutter placed underneath the filter, and a second linen cloth be put between them to receive the liquid which may proceed from the sides and conduct it to the gutter, with the impud filtered liquid. The bucket or part P of the cock R. being placed at the end of the pipe of the boiler and kept thereby means of the stop S. that the cock of the pipe B. open the cock N & R. taking care to stir the agitator P briskly during the time the liquid and its deposit runs on the filter. The liquid being drawn off to the height of the cock R. close this cock, and recharge the boiler with fresh matter, and proceed as in the first instance. When the liquid above the cork C. of the filter is clear let it run into the gutter by means of a moveable pipe suspended underneath a seat by a cord, & which pipe may be moved from one cock to another is required. The colored substance is afterwards put and boiled in the boiler figure 7. in the manner already described, and then run into the filter figure 8. by means of the tube B. being sufficiently drained it is then to be carried to the strainer figure 9. when it must be washed (to clear the dark solution, of which mention has been made for boiling the colored substance) with hot water proceeding from the side of the carriage figure 2. which water must be raised up to the strainer by means of a pump or otherwise.

7

117

The prismatic water, of the two boilings, of the calcined matter being brought into the common solution in the reservoir figure 10, by means of the pump of this reservoir figure 11, let it fall into the Boiler T, figure 1, by the cock C, and the pipe O.

The solution of the prismatic being concentrated in this Boiler until it forms a pelleted (reference of my patent of the 11th June 1832.) on the surface of the boiling liquid open the cock in the pipe V (which is to be about 4 inches diameter) and the solution will fall into the crystallizer figure 12.

When the prismatic is crystallized and the solution cooled, open the cock B of the crystallizer figure 12, break the crystals opposite to the tube and the matter water will flow (that is to say, the solution of carbonate of Potash) into the reservoir figure 13, after which the crystals are to be thrown on to the filter figure 14, to be drained, and the solution conducted (by the pump belonging to this reservoir) to the boiler figure 14, for the purpose of being concentrated. When the calcined substances are sufficiently broken and drained in order to obtain the required weak water close the registers X and V, of one of the stoves figure 15, in order to direct the heat and smoke into the other stove.

Place the retained substances on the hurdles P, of the first stove and when the required number of hurdles are placed in it, that the door A, of which the projecting ledge L, will enter into the groove B, running all round and filled with sand, open the registers, and when the matter has become dry, shut them again and take out the hurdles.

Having concentrated the solution of Potash in the Boiler figure 14, &c. the calcined matter being broken as hot as possible, it is to be carried to the boiler figure 14, placed close to the boiler 14, and mixed as it has been described in the first patent. The liquid must be added until the calcined matter becomes cool, and so on for succeeding operations.

For the second crystallization, the apparatus does not differ

105

in the huler figure 18. This will be afterwards dissolved to the consistency of fig. 19. N.B. The mixtures so far to use those given in my Specification - patented on the fourteenth December 1832. Only parts of animal substance and of Potash to which a foreign substance has previously been added.

In fact all the materials used in the manufacture of bristles may give the same subsequent result if treated in my manner and by my economical way of manufacturing.

Process of Scouring.

Scour the wool in the flues, from its grease may be by the ordinary way, or by means of a strainer managed by a crane in wheel. Strain the wool in such form as much as possible from grease, brained and washed (14) after this operation fill another strainer loosely with the same wool and put it in bath No. 1. (13) soon after the wool has been in this bath it should be raised, and lowered again and allowed to remain for ten minutes, then be stirred about for a short time & raised again. If the operation is not completed place the strainer or vessel containing the wool, on a stand or frame for ten minutes then turn it on the other side and leave it for ten minutes more afterwards introduce it into the No. 2. and treat the wool in the same manner, and during the same time as in No. 1 or about.

The bath 1st will be found more serviceable and convenient for wool which has been recently shorn from the animal and in all cases when the wool is in the flues, because the wool sorted into cloth has in general been fulled and therefore the bath 1st & 2nd are considered as less necessary.

For common wool it is generally necessary to pass it into bath No. 1 which will entirely destroy the follicles that cover its roots, and which follicles prevent its whitening the same when used in the ordinary way, or if it does whiten it the colour is soon destroyed and the cloth becomes white at the edges and so on. In the case of cloth for lining servants' caps

washing, or when employing bath No 2.) the wool may be put into bath No 3 for drying as is the case when operating on cloth or fullled wool, but the omitting of these operations is not recommended as it will be much less perfect.

The bath No 2 intended for blankets, cloths, or stuffs may be formed in the ordinary vessels used by dyers, and the work conducted in an ordinary case over salts, with the observation that all their parts be exactly prepared by the dyer, as an inequality of shade would be the result of a slight error in this operation. Wool may also be put in a large slate into the salts. Wool in the place fasted into the bath, Nos 1 & 2, and afterwards washed with water will be free from all smell proceeding from the oil or grease which it especially contained, when, and treated in the ordinary way. However good and complete may have been the means employed to clean and dress it, all strong perfume worn or left, has well which it is desirable to get rid of. General, means of applying the mercurial (15) is of fixing the laudanum of wool or cloth, and other substances in general fit for dyeing by the application of protosolts of iron &c (16).

16. Wool commences first with wool in the flax, then with that in cloth, stuff or piece, and afterwards, with wool and all other wools, or materials in this. Besides the two principle methods of applying the mercurial, described in my first patent, there are many others which can be resorted to, as for example. 1° In producing a change in the protosolts on the wool other than this change shall be simply produced by the decomposition of the protosalt of iron, which comes in contact with the air, arising from decomposition of the salts, by conducting a current of hot air to the wool to oxygenate the protosolts, and to produce that oxygenation in a prompt and equal manner on all parts of the mass of wool.

2° On the number of immersions of the wool in the bath, 3° on the manner of preparing the bath, on treating and maintaining them in a fit state for subsequent use when applying the mercurial, and on so doing with economy and economy. 3° On the employment of the various machinery, vessels, utensils, &c, constructed for the diverse operations of applying the mercurial, when these vessels are arranged in a proper manner to carry on the

and with complete, even and constant, 5th. The first method of the first patent may be dispensed with, that is, to say, that first - look solely to decomposition, and the operation of applying the moderate or the other operations, may be carried on as if the end of this decomposition had been arrived at. The wool having been prepared by the bath, 1. & 2. and as already pointed out, is to be put (formulating it by the first method of the first patent) into the vessel or strainer, which vessel has been previously placed in the bath No. 3. The wool may be packed rather close when the quantity required is so placed, since the wool out of the bath and before it again comes immediately repeat this operation a second time, though the wool on the frame. The wool thus placed (the vessel being turned on its other side during that time) will be sufficiently drained in half an hour? (or at least that part which is in the upper part of the vessel) to be put into the bath No. 4. The small quantity of wool which lies at the bottom of the vessel should be squared or woven before it is put into that bath. The more the wool has been drained after its last washing, before being put into bath No. 3, the better in fact if it be quite dry it would be preferable, but in that case it will be the easier with greater difficulty, and more wool then be taken and to put to go out a quantity into the vessel, as it would be necessary to stir it about in order that it might be evenly distributed in the bath.

For bath No. 4. The wool placed in the strainer is treated as directed in the former specifications, and, after having remained there for about $\frac{1}{2}$ of an hour, take out the vessel and place it on the frame in an inclined position (17) for about 15 minutes and then change its position from 3 to 4, and vice versa in order to equalize the distribution of the liquid upon the wool, which is to be spread afterwards on a hot stone till the per-oxidation is completed.

Being placed again in the strainer it is removed to bath 5, as soon as it touches the liquid, let it be lowered as quickly as possible to a level the middle of the depth of liquid, when the wool may be turned over with facility by means of sticks, after having remained in this bath for about 15 minutes, take out the wool and place it on the frame, one

be treated as before, because the wool will not heat in water and the
 heat will be lost. In this case it will not be necessary to introduce the
 wool into the hot stone, but if, instead of putting it into the bath 5
 it should be determined to submerge it into the bath 4, as is done in
 ordinary cases, to fix or apply mordant by the second method of the
 first specification, it will be found convenient and desirable to pour
 it at second time to the hot stone, and in the case of the latter mode
 of applying the mordant, it will be well to apply that method of
 application after each immersion. It may be observed and well
 noted however, that should be made in the bath 5, without placing
 the wool on the frame, except for a short time only after the last
 immersion, in applying the mordant by the first method, the mode
 of placing the wool into the bath may be changed if desired. After
 pouring it into bath No 4, at 3 degrees of the thermometer, pour into bath
 No 3 at 6 degrees, but at each immersion ~~one~~ ^{one} of two gills will
 be required, of course to be added to the water already formed, not
 to the use of these baths. Bath No 6, to be used about the same
 way as No 5. For bath No 7, the wool may be scattered into the
 frame placed on the vat to be withdrawn at the end of the
 boiling with every care after this bath, and may be treated
 to after each one of the operations of mordanting which precede
 it. Mode of applying the salts of copper as a mordant for fixing
 the salts of that metal on fibrous substances. This mode of applica-
 tion to be repeated upon. I must add to the directions of the
 first specification, that: 1° It is desirable that the solution
 which the bath 3 is formed with lime for example, should be as
 infinite 3 or 4 times the length of the vessel, in order that a normal
 measure of lime may always be contained in the vessel, and
 that by a very little, when this excess may fall to the bottom and
 remain there as a deposit. By this means the copper fluid of the
 vessel will be limited when the wools are plunged into it.
 2° What ever may be the nature of any other materials to be mor-
 danted, be it to those latter ones, in which you are operating, follow

(9)

the same directions, before going on repeating the first method with a carbureted alkali or bath, such as No. 3, and if the second method is further other to the substance. 3. The last bath into which the substance should be passed may be either 3 or 4. McNeill specifies No. 3, and whether the materials should or not afford a plenty of water, but I recommend using the following substance, as tested by the author, and to be passed into the proper bath to obtain a block of such freedom as to suit the action of the acid and the bath.

4. The residue of iron and of copper may be also fixed on the substance all the same time by means of the bath No. 4 composed of the salts of iron and of copper. Or simply the operation being performed with a bath of muriate of copper, as it will be thought more convenient.

5. For conducting by the salts of copper the alkaline bath No. 3 may be heated to a red heat, or even to incandescence, especially if it is chosen to melt salt at the same temperature.

The salt being now made ready to receive a red color is to be treated, for long time or treated from about 15 to 25 minutes on any fire-heater. If it is intended for blue the salt of iron must be introduced into it, either to this last bath or after this immersion at intervals of 10 minutes. But the salt must not then be raised so early, as if the bath is hot fully this salt of iron will not suffice in solution of itself to keep up the quality in all parts of the bath. It will bring over on the blue salt bath the following of the green, if the iron is introduced only to give some brilliancy, however, it belongs to the blue only may be introduced to the bath salt, when it will give the better result.

They may also be omitted, when it is required that, for

No. 5, is only a preliminary bath when rods are applied. Other steel may be applied before, during or after the saturation of the rods, or by means of firebrick, to constitute a finishing bath (79). This is one kind of many other bathtubs which it is proposed to construct, as it will be appropriate to follow patent practice.

Observations and notes referred to:

First bath from No. 1, inclusively, are intended to delineate some of the art of which my claims are founded. The number to be looked for in the application connected with the plates, etc., in my number, deposited in the Patent Office.

If the bathtubs are not obligatory, and they may be constructed of wood or of metal, I might save some of them as are intended to be tankards, for which wood is preferable.

After a bath or operation is finished, the bath shall be brought into the plates, already indicated in speaking of their formation, be fired, commencing with the operation. Big bathtubs are understood, all sorts of liquids, gas, vapor, or steam, to the action of which the little bathtubs are exposed. All the bathtubs shall be heated by steam.

The heat may be heated by means of the hot stone bath, by passing it through a cast iron cylinder, placed by the fire place, or in a double chimney of a furnace, or by steam passed through a double conductor, or pipe, as indicated in the plates, or by any other convenient mode. In all cases when account of air is forced in by a pair of bellows, they should be placed at such a distance from the fire, when the heat proceeds, as will insure a perfect and a general diffusion of air on the upper plate.

If, also, with the bathtubs, should be covered, their upper parts, and be covered with a coarse woolen cloth, this will leave a passage for the humidity to pass without losing much of the heat which has been introduced, this will be found a very advantageous, mild, and superior, to the ordinary fitting up of stoves, where the humidity passes, making buildings, and especially through openings in them, and a person or heat than humidity, passes off that way.

The following are three of the many formulas of different materials, and proportions, given in the project. 1650 to 9000±3000 feet
of water, 100° to 120° F. 100° to 120° F. and 0° to 10° C. which
will be 50° feelings, and 100° F. will be 100° with 50° thermal
heat of the water. The project of the following should be followed, the
idea of course not being strict.

The most popular must be probably, filled with small pieces of
broken either of glass, lead or iron, and forwardly to be attached
to the neck, or forward end of the roller, so to be arranged
as to be referred to 3rd and 4th in the place of this disk, which may be
recalled to the mind, that it must not be fast to the cylinder
until after it has been charged. If then it is required to render
this roller And Bth and the cylinder Cth capable of the same, a
figure Dth must be employed, which turns its own self first on
its platform Eth then going round to be settled on the roller And figure
and turns Bth affixed to the ground therefore from its immobility
and being its self solid, but after it is done it to be fast, so
to form its role only on figure without parts, the carriage ought to
be no thicker than

Then the correct voltage and resistance of the galvanometer must be sufficiently long, from the staffing box to the place in order to prevent the forced supports of II from being a justifying the charging and discharge of the source of C.

10th. The following report has been made to the Legislature by fellow
legislators from various parts of the state to become
a law:—In that case the state is to be considered as being at
the first place of the former, and in the time of one year for trials may
be held, if possible, in the city of Toledo, and the same, entering the
city of Toledo, as in this last, the day of trial, will be employed
for the second trial, and the place or a full half of their electorate
selected. 11th. The time of holding any of the trials will be all
of the time of the 1st of January, and the 1st of April, in the broken
year. B. the first 15 days of January after the 1st of January has been

15th. The water will then be taken off from the carriage by the tank C, and this tank will be filled with cold water before another carriage is ready, and again drawn off from the carriage. Close the tanks. R.C. take hold of the carriage, the posts to be taken hold of the tank B. of this carriage, figures 3 and 4, which may, must be raised to a convenient height, and then be turned over, the carriage will then fall out of the carriage E, and before this occurs it is to be seen (figure 23) (or some other place) and bottom through the carriage gate A, which is to be closed immediately after.

16th. Scatter reinforcing of the frame - Specifications.

17th. Having drawn the construction of the bath, in my former specifications, to illustrate it, it may only be said that the bath alluded to, and to be used in the United States, the country be stated,

This construction may be understood for a coagulation bath, that will be used for 14th. It is absolutely necessary that wool - intended to be spun - should be well washed. The system of knots, and at present employed, is very defective. From many instances, part of the wool, being creased and pressed into small pellets, by the stocks, usually combed, and turning it over, becomes unfit to receive the dye. It occurs, it is perfectly, that different kinds of felt, are sometimes, used in combination with coagulation from the bath. But the employment of this method is now mounted, and must completely obviate this difficulty, and advantage, indispensability of which a much greater quantity of wool can be washed in the same given time. This can be done by any of the means now employed for the purpose (see plate 3.)

18th. Having placed in a vessel of water, put the wool on the end of the stick A, then put the vessel of water over the vessel by means of the handle N, and the stopper H. The wool will then fall into the water, the vessel of which will conduct it towards the spike M, and thus securely from one spike to another, until it be conducted toward, the basin V, which is a receiver of the vessel it comes from the stick I, if it is not in the stopper H, will cause the wool (when washed) for that it may fall into the carriage or basket w.

14. The current of water in the machine can be regulated by gate valve
and when there is a flow of 3 ft. per second, that the water may
be caused to run over the spikes, in the required facility and quiet.
Also in all cases regulating the depth of water under the machine
when it is in operation, so the current will be trouble, the
depth of 3 ft. and no less, will be sufficient for an acceptable
flow of water, on the other hand, may be obtained in lieu of the
gates of land or banks of this machine of black chain below, or
on the sides of the river if the land marked GR. NO. 1 is to come
regularly back and forward in that part of a circle, when
it is on the spikes, the which lay hold of the bank.

This machine may be used to extract of metal or in part
frontal and in part of iron. The speed of extracting it
is always to be understood that this machine is used for that purpose.

15th. The operation of this engine for the sake of iron
or other metal extractively, may be used in a particular region
of the matter after which, the operating is not intended to be
carried out both the 3 ft. or 4 ft.

16th. The slant of 30° may also be employed and will be
convenient on the bank of the river, on the side of the 3 ft. or 4 ft.
liquid, it will be necessary after each movement to clean the sand containing
the water as a frame of iron, which it is to be placed in on the side
of the bank, the sand which is placed in its side will be
naturally found to be sufficient to 3 ft. to 4 ft. of water for
safely, for the lack of water 3 ft. is the water which is present in
a quantity of sand and sand is carried to the water which should
be taken to prevent the water which is used to filter or again

the depth of the 3 ft. with the 3 ft. or 4 ft. of water, for preventing that
of the water and sand to mix together so brought as near to
the side of the bank, the sand which is present in the water dissolved
in a quantity of sand and sand is carried to the water which is
the water which is present in the 3 ft. or 4 ft. of water as
the sand which is present in the water which is present in the water

will be much more willing after the bath. Nos. 3, 4, & 6, have been used, those when passing with the other baths. It appears, the use of the latter bath No. 6, it may be well to observe that the liquid should be well and fully distributive, but that the wool should be strained as much as possible when it is put into bath No. 7. If it is even dry, so much the better. The practitioner, it may be fed upon cloth or other substances, intended to be dyed black by various means, to good to them, what is practically termed a bleaching. It may be done by way of double decomposition, by using one of two substances previously which has been spoken of, the color of saffron for bath No. 6, by dissolving the oxide of iron in an acid bath formed with a soluble product, for instance, before or after producing black in this color. This black black has likewise been produced by saffron, and it can be so done yet, with the application of the oxide of iron by my process, and again the double decomposition in using the other two products, in order to obtain the black shade, can be obtained on applying the protocols or bath salts formed by the process already given.

Other Observations

All the components of the acids, or utensils employed with the acid baths, should be varnished to defend them against the action of the acid, and the varnish be renewed from time to time.

Instead of using liquid ammonia in order to desinfect the blue shade, you may employ ammonical gas, more or less dry in the stove. In fact the ammonia may be introduced in such manner as follows, the best results, and the same observation applies to the acid bath. The oxide of iron may be precipitated after bath No. 4, without taking the wool out from the strainer, by introducing a current of warm air into its interior as described in the first article, insulating, covered with them.

The oxide of iron may also be applied by legimation (bath plates and applications), after the wool has remained about a quarter of an hour in the acid bath, it is cut and when it is nearly dry off introduce this current of ammonia of alone for 1/4 of an hour.

Observations on the bath. - No. 1 is all the acid, except nine parts, this part is not required, and some acid only, as the bath of 10° about 30°, is fit for this bath. - 10°-20° for long time, - 16°-18°, for 10-15 min., and for 10-12 thumb bds, taking care to stir it about and to take only the small salt parts from it. - 30°-34° bath composed of caustic carbonate well with salt, adding therefore degrees as the bath is likely to alkalinize, though for bath 30°. Water alkalies must be avoided as much as possible when painting on bone, & substances principally for bath No. 3.

At the 30° bath may be rendered neutral, before it is employed as well as in course of operation. This is done by an excess of the salts of soda, caustic, or other alkalies or carbonates, but more particularly by the carbonate of lime. - Then it may be necessary to render it a thing of much importance, and is establishing a sort of clear distinction between the species, and those already known, so that, by fitting the new or new, or adding it with the carbonate of lime, that by any process the bath can be made of 10-12°, & are kept constantly neutral to produce the effect of fixing the bone in a more elevated state. Whereas by the other species the bath becomes more alkaline and during the process of their use, the bath is prepared in a more than neutral salt, so that the carbonate of lime is added to the bath of about 10° degrees of the extremer for salts, 1/2 of alkalinized carbonate by an acid. Then add to the solution when about 16° to 21/2 degrees of alkalinized, as will contain a alkali, for example, lime, the alkaline principle of which requires about three half of the same proportion of alkalinized, the soap is to be present.

Another mode may be employed to neutralize this bath, viz. after having had the alkalinized carbonate boil the solution with a sufficient quantity of oil, & so to dilute the alkalinized that after this extraction shall have taken place, a very trifling traces of oil or grease may remain in the bath, and so salted of oil, & of alkalinized, the neutralized, or watered with a caustic alkali, employ that which has been combined with the alkalinized carbonate. Instead of employing a deproteinized solution, you may use the weak solution of an alkalinized carbonate or of a caustic alkali which need be boiled with some animal substance, & a wet wool cloth or white

the body of the animal, just above the heart with several pieces of strong linen, which may be impasted by a dipper or by this means and be sufficient to cover the bottom of the reservoir, to prevent the loss of any portion of the dipper which may be found there. This dipper must be withdrawn from time to time to facilitate the filling of the reservoir, so placed sufficiently high to allow the liquid to be conducted to the said vessels, by means of pipes or channels, because the liquids can be transported much more quickly and with less waste, especially by transporting them by hand.

Converses Figures 11, 13, 26, 27, and there, Figures 10, 12, 19, & 26.

Should the said tank be six feet high, the first one being built near the general about four feet above the ground, the main factory should be flagged, especially near the cylinders, should be built upon a flat and right about.

Any practical man will easily perceive the difference between the common process of dyeing silk, and other by the process of iron, and the one described above, in manufacturing (being aware of the entirely different nature and properties of the practically, one of the facets of iron); and understand why a process, which is easily, tolerably well, on these two materials, does not succeed on wool, that must be submitted to so many trials, operating in order to its being turned into cloth. — Although nothing precisely by the means indicated above, I have, yet experience has taught me that the materials they are good either for the composition of baths, their degree of saturation, and the degree of temperature; the construction of machinery described in the plates and its arrangement and employment, the more advantageously will be the results obtained. But I do not mean to say that, by a combination of the present effects, or various improvements, cannot be obtained. Some of the advantages of the new principles, to from its investigation, are almost unlimited. But only as regards the fixation of practice, or, But also for the obtaining of new colors, by detaching too numerous to be inserted here. I shall mention how but one example to show that this improvement may be extended without entailing the application of dipping. — The process of wool dying are known to consist in the fleece, the other in the piece, by this process I can produce a color dyed in the piece, that will exhibit all the characters of having been
